UNITED STATES PATENT OFFICE.

ARTHUR NOAH FLEAGLE, OF BALTIMORE, MARYLAND.

BOTTLE-CAPPING TOOL.

1,190,138.

Patented July 4, 1916.

Application filed October 8, 1915. Serial No. 54,813.

To all whom it may concern:

Be it known that I, ARTHUR N. FLEAGLE, a citizen of the United States, residing at Baltimore, in the State of Maryland, have 5 invented new and useful Improvements in Bottle-Capping Tools, of which the following is a specification.

The present invention relates to a bottle capping tool for household use.

10 An object of the invention is to construct a simple, cheap and thoroughly effective hand operated tool which will easily and quickly place an ordinary crown cap upon the bead of a bottle neck so as to hermetically seal the bottle to preserve the contents thereof.

15 With the above and other objects in view, the improvement resides in the construction, combination and arrangement of parts 20 set forth in the following specification and falling within the scope of the appended claim.

25 In the drawings: Figure 1 is a view of a hand operated bottle capping tool constructed in accordance with the present invention illustrating the operation thereof, Fig. 2 is a central longitudinal sectional view through the same, Fig. 3 is a transverse sectional view approximately on the line 3—3 of Fig. 30 2, and Fig. 4 is a horizontal sectional view approximately on the line 4—4 of Fig. 2.

35 The well known tin crown and cork disk employed by manufacturers of bottled goods is considered one of the best methods of sealing bottles. The cost of machines required for applying the crowns prohibits the use of the same in households. Therefore, 40 it may be considered the primary object of the present invention to provide an efficient but inexpensive tool for applying the tin crowns to bottles which may be easily and quickly operated and which will occupy only a small space when not in use.

45 The improvement consists essentially of a bottle holder 1, a lever 2 and a capping piece 3.

50 The holder end includes a longitudinally extending arm 4 having one of its ends widened and bifurcated to provide spaced side members 5—5. The space between the members 5 is slightly greater than the cross sectional diameter of the neck of the bottle below the outwardly bulged portion 6 thereof which is disposed below the beaded lip 7 55 of the bottle 8, and the connecting wall between the members 5—5 is rounded, as at 9,

and preferably flared inwardly or toward the handle 4. The upper surface of this rounded wall 9 is rabbeted or otherwise formed with a round groove 10 and the 60 lower wall of the said groove is rounded, as at 11, to correspond with the lower portion of the bulged part 6 of the bottle neck. The groove 10 is tapered to a feather edge as it connects with the sides 5—5, and the 65 rounded shoulder 11 engages with approximately one-half of the bulged portion of the bottle neck. By this arrangement it will be noted that the bottle will be effectively sustained upon the holder member 1 70 and that its beaded lip will be projected above the upper surface of the said holder. The members 5—5 at their outer edge are extended upwardly and at a right angle to the longitudinal plane of the hollow and the 75 widened portion or bottle seat thereof, as indicated by the numerals 12—12. It is to be understood that the parts are referred to as when the device is in its horizontal position or operative position. The extensions 12—12 are provided with openings 80 to receive the trunnions or pivot members 13 provided upon the widened head 14 of the lever 2. The lever at a suitable distance from its head 14 has an elongated slot 85 15 through which is passed a pintle 16 that connects the spaced ears 17 of the capping piece 3 to the said lever. The capping piece comprises a tubular member 18 which has its bore of a size sufficient to snugly receive an ordinary crown cap, and the lower edge of the bore of said capping piece is angular, corresponding to the pitch or angle of the crown caps which are adapted to be arranged in the said capping piece. The 90 capping piece 3 is provided upon its sides with diametrically opposite lugs 19, and the members 5 have vertically extending guide pins 20 which pass through suitable openings in the lugs 19.

100 It is, of course, obvious that the center of pressure must move in a constantly vertical direction and that it is essential that the capping action take place in as nearly horizontal plane as is mechanically possible. So 105 with the construction illustrated and described the slot 15 of the lever 2 permits of the cap piece 18 moving upon the guide members 20 in a vertical direction, the guide members 20 positively retaining or 110 holding the capping piece 3 in such position so that the cap will be properly fed to the

beaded lip of the bottle. In order to more fully aid in protecting the bottle against breakage, I have found it desirable to provide the shoulder 11 of the holder 1 with a 5 facing of some suitable compressible material, such as felt and which is indicated by the numeral 21.

From the above description, taken in connection with the accompanying drawings, 10 the simplicity of the device, as well as the advantages thereof will, it is thought, be perfectly apparent to those skilled in the art to which such invention appertains without further detailed description.

15 Having thus described the invention, what I claim is:

In a hand operated tool for applying crown corks to the beaded necks of bottles, a holder including a handle having a 20 widened end which is centrally slotted to provide spaced side members, the connecting wall between the same being rounded and being grooved at one of the edges thereof, the opposite walls provided by the

groove being tapered inwardly of the said 25 side members and the lower wall thereof being round, the ends of the side members being inclined outwardly from the groove and provided with extensions at an angle thereto, a lever having one of its ends pivotally 30 secured between the extensions of the side members, said lever having an elongated slot disposed above the mentioned groove, a capping member having a cylindrical body provided with ears arranged to the opposite 35 sides of the lever and having a pivot member passing through the said ears and through the mentioned elongated slot in the lever, lugs formed upon the diametrically opposite sides of the capping member, and guide 40 pins on the side members of the handle passing through openings in the said lugs.

In testimony whereof I affix my signature in presence of two witnesses.

ARTHUR NOAH FLEAGLE.
